United States Patent Office

Des. 234,228
Patented Jan. 28, 1975

234,228

SYRINGE

Ronald E. Spiegel, Oak Brook, Ill., assignor to Cenco
Medical Supply Corporation, Chicago, Ill.

Filed May 14, 1973, Ser. No. 360,151

Term of patent 14 years

Int. Cl. D24—04

U.S. Cl. D83—12 A

FIG. 1.

FIG. 2.

FIG. 3.

FIG. 4.

FIG. 1 is a front elevational view of a syringe;
FIG. 2 is a side elevational view taken from the right
side of FIG. 1 and identical to the appearance of the
syringe if viewed from the left side of FIG. 1, with the
exception of the graduation in numbering;

FIG. 3 is a top plan view of FIG. 1; and

FIG. 4 is a bottom plan view of the syringe.

I claim:

The ornamental design for a syringe, as shown and
described.
